UNITED STATES PATENT OFFICE.

RICHARD TEICHMANN, OF BROOKLYN, NEW YORK.

GAME OF SKILL.

SPECIFICATION forming part of Letters Patent No. 558,325, dated April 14, 1896.

Application filed December 27, 1895. Serial No. 573,461. (No model.)

To all whom it may concern:

Be it known that I, RICHARD TEICHMANN, a citizen of the German Empire, residing in Brooklyn, in the county of Kings and State 5 of New York, have invented certain new and useful Improvements in Games of Skill, of which the following is a specification.

This invention has reference to an improved game of skill, to which I have given the name 10 "Game of hearts," and in which a rolling body or indicator is to be balanced and brought to a goal on a suitable supporting-plate; and the invention consists of a game of skill, which comprises a rimmed supporting-plate having 15 a goal and subdivisions extending from said goal, and a rolling body or indicator that is placed on said plate, so as to be transferred to the goal, said rolling indicator being formed of two rounded-off or heart-shaped sections 20 connected at right angles with each other at their adjacent ends and made from one integral blank, as will be fully described hereinafter, and finally pointed out in the claims.

In the accompanying drawings, Figure 1 25 represents a top view of my improved game of skill. Figs. 2 and 3 are top views of modified forms of the same. Fig. 4 is a vertical central section of the same on line 4 4, Fig. 1. Fig. 5 is a like section showing a slightly- 30 modified form of the supporting-plate of the game. Fig. 6 is a perspective view of the rolling indicator, drawn on a larger scale. Fig. 7 is a top view of the blank from which the rolling indicator is made.

35 Similar letters of reference indicate corresponding parts.

Referring to the drawings, A represents the supporting-plate of my improved game of skill. The plate A is made of circular, 40 square, or other shape and of sheet metal, hard rubber, cardboard, or other suitable material and provided with a raised rim a. On the depressed portion of the supporting-plate A is arranged a goal G, which may be concentric to the rim a, or located at any other point on the plate A. The remaining space 45 on the plate A is divided by lines d into sections, which are marked with any suitable words or quotations, according to the name 50 and character which is to be given to the game.

A rolling body or indicator B, which is

formed of two rounded-off or heart-shaped sections b b, that are arranged at right angles to each other and connected at their adjacent portions, is placed on the plate and has to be played into the goal G. To render the game somewhat more entertaining and interesting, the goal portion of the plate may be slightly raised from the under side, as shown in Fig. 3, so that the difficulty of playing the rolling body into the goal portion is increased. Any other similar obstructions may be arranged on the plate A by raising the supporting-plate at other points. The rolling body or indicator 60 B is made of a single blank having a central connecting-web b' between the two sections of the blank, which sections are separated from each other by laterally-inclined slits b'', so that the rounded-off or heart-shaped sections can be readily bent up and placed in position at right angles to each other. The rolling indicator can also be made of cast metal, such as pewter, instead of sheet metal, or by soldering two separate heart-shaped 70 pieces together at right angles.

The supporting-plate is either held by the fingers at the rim or placed on the palm of the hand and slightly tilted one way or the other, so that the indicator rolls freely from 80 one side of the plate to the other. It requires some skill in arresting the movement of the indicator when it runs across the plate so as to place it in the goal. This appears to be done easily enough; but on trying it the 85 player will find that the indicator has a tendency not to stop in the goal, but to shoot over the same toward one side or the other of the plate. If the player succeeds in stopping the rolling indicator, it will be found more often 90 outside of the goal in one or the other of the marked sections. It takes some time and practice to bring the indicator into the goal.

The subdivisions of the supporting-plate that are arranged around the goal portion G 95 can be provided with suggestive and humorous inscriptions, which are either printed in suitable colors on the plate or on a separate layer of paper or other material that is cemented onto the depressed portion of the 100 plate, so that thereby a certain comical and ludicrous element is imparted to the game, especially when the same is played by several persons in succession and when the inscrip-

tions on the sections on which the rolling indicator finally arrives are read off for the benefit of the company.

The title and inscriptions of the game can 5 be varied so that thereby a considerable range for the game is obtained.

Having thus described my invention, I claim as new and desire to secure by Letters Patent—

- 10 1. A game of skill, consisting of a rimmed supporting-plate having a goal portion and radial subdivisions around said goal portion, a rolling indicator or marker having two rounded-off or heart-shaped sections arranged 15 at right angles to each other and movable on said plate, substantially as set forth.
- 15 2. A rolling indicator for a game of skill

made of one integral piece composed of two rounded-off or heart-shaped sections which are arranged at right angles to each other and 20 connected at their adjacent ends, substantially as set forth.

3. A blank for a rolling indicator, consisting of two heart-shaped or rounded-off sections connected by a central web and having 25 inclined slits at opposite sides, substantially as set forth.

In testimony that I claim the foregoing as my invention I have signed my name in presence of two subscribing witnesses.

RICHARD TEICHMANN.
